[57] CLAIM

The ornamental design for a timing light, as shown and described.

DESCRIPTION

FIG. 1 is a top view of a timing light showing our new design;

FIG. 2 is a side elevational view thereof;

FIG. 3 is a bottom view thereof;

FIG. 4 is a front elevational view thereof; and

FIG. 5 is a rear elevational view thereof.

The side of the timing light not shown is a mirror image of the side shown in FIG. 2.

*Fig. 1**Fig. 2**Fig. 3**Fig. 4**Fig. 5*
